(57) **CLAIM**

The ornamental design for a hearing protector, as shown and described.

DESCRIPTION

FIG. 1 is a perspective view of a hearing protector our new design;

FIG. 2 is a top view thereof;

FIG. 3 is a bottom view thereof;

FIG. 4 is a front view thereof;

FIG. 5 is a rear view thereof; and,

FIG. 6 is a right side view thereof, the left side being a mirror image of the right side view.

Portions of the drawings shown in broken lines do not form part of the claimed design.

1 Claim, 3 Drawing Sheets*FIG. 3*

FIG. 4

FIG. 5

FIG. 6

UNITED STATES PATENT AND TRADEMARK OFFICE
CERTIFICATE OF CORRECTION

PATENT NO. : D668,392 S
APPLICATION NO. : 29/390654
DATED : October 2, 2012
INVENTOR(S) : Lars Carlborg
